CLAIM

The ornamental design for a shaft portion of a skeg for a surf sailing board, as shown and described.

DESCRIPTION

FIG. 1 is a left side elevational view of a shaft portion of a skeg for a surf sailing board showing our new design; FIG. 2 is a front elevational view thereof; FIG. 3 is a rear elevational view thereof; FIG. 4 is a top plan view thereof; and, FIG. 5 is a bottom plan view thereof. The right side is a mirror image of the left side thereof. The dashed lines show environmental structure that is not part of the design.

FIG. 1

FIG. 4

FIG. 5

FIG. 2

FIG. 3
